OIL WELL APPARATUS

Joseph F. Moody, Tulsa, Okla.

Application July 19, 1933, Serial No. 681,079½

22 Claims. (Cl. 294—91)

My invention relates to improvements in oil well apparatus and particularly to elevators such as are used for manipulating the drill or rod in the well hole of the type as disclosed in my Patent No. 1,766,920.

An important object of the invention is to provide a novel detachable wear plate against which the rod bears and by which it is supported.

10 A further object is to provide a wear plate with means for permitting the same to be fastened and uncoupled easily.

15 A still further object is to provide novel means whereby the pivot pins serve to firmly hold the detachable wear plate to the body portion and additionally serving as means for permitting the easy insertion of the cotter pins.

20 Another object of the invention resides in the provision of novel closure elements or dogs for the elevator opening and which are held in place by the detachable wear plate which supports the rod.

25 A still further object of the invention is to provide a device of this character which is relatively simple in construction, inexpensive of manufacture and highly efficient in practical use.

Another important object is to provide novel latching dogs whereby the rod is locked within the opening in the elevator.

30 The invention also resides in certain novel features of construction and combination of the various parts and in modes of operation as hereinafter described and claimed, reference being had to the accompanying drawing which illustrates the now preferred embodiment of the invention.

It is to be understood that the invention is capable of various modifications within the spirit and scope of the subject matter claimed.

40 In the drawing wherein the same reference characters have been used to designate the same parts in all views,—

Fig. 1 is a top plan view of an elevator incorporating my invention, the bails which connect the elevator to a hoisting apparatus being shown in dotted lines as swung down to horizontal position;

Fig. 2 is a section taken on the line 2—2 of Fig. 1;

50 Fig. 3 is a fragmentary top plan view of Fig. 1 showing the wear plate removed so as to expose the novel latch dogs and also showing a broken section through the left dogs and exposing the stop means carried by the body portion of the elevator;

Fig. 4 is a fragmentary top plan view of Fig. 1 showing the wear plate removed and exposing the relative position of the dogs in unlocked position, the right dogs being entirely released from their normal seat and the left dogs about to be released;

Fig. 5 is a group perspective illustrating the wear plate, one set of the latch dogs and the eccentric pin and cotter pin therefor.

Referring specifically to the drawing the elevator comprises a body 5 which is provided at opposite sides with ears 6 which are horizontally slotted, as at 7, to receive the bails 8, shown in dotted lines, (swung down out of their normal elevator-supporting position) and which connect the elevator to the hoisting apparatus.

The bails 8 are secured in the ears 6 by means of pivot pins 9, arranged in openings 7' located in the ears,—it being observed that each member 9 is an eccentric pin and has a reduced end 9' of substantially uniform circular configuration through which a cotter pin 10 extends transversely and adjacent the inner exterior surfaces of the ears 6. Such a pin structure will adjust more readily on the wear plate and also will allow the use of larger and stronger pins as the openings 7' in the ears 6 can be drilled lower than usual; and the portions 9' of the eccentric pin 9 will still be high enough above the wearing plate to allow the notch 28 in the wearing plate to be high enough to permit the bottom of the plate to be left solid and thus stronger than heretofore. The novel wear plate 16 cooperates in holding the pivot pins 9 in fixed position, as will be presently explained.

35 Referring now to Fig. 3, it will be noted that the top surface of the elevator body 5 is provided with a circumferential groove 11 which is enlarged at the front of the elevator as at 11' on either side of the work receiving slot 12. At the rear sides of the groove 11 are abutments or teeth 13 which provide stops or locking abutments for the latch dogs which will be presently described. The groove 11 and slot 12 define the central boss-like member 14 which as viewed in Figs. 3 and 4 has the appearance of a fairly full moon.

The latch elements comprise upper and lower dogs 15 and 15' respectively. The lower dog 15' is arcuate in plan and is provided at its forward end with an enlarged laterally extending nose portion 17'. An opening 17 is located in portion 17' and adapted to engage a stop element 18 carried by the body portion 5. A second opening 19' is carried intermediate of the ends of the dog 15' and serves as a socket for a pivot carried

55

by the upper dog. It is to be noted that nose portion 17^a of dog 15' engages the outer wall of groove enlargement 11'. This prevents latch element or dog 15' from being rocked outwardly in 5 groove 11 by contact with work within openings 12, 29. But upper dog 15 may be rocked slightly in groove 11, and relatively of dog 15' (see Figs. 3 and 4) to disengage its shoulder or notch 25^a from the abutment or tooth 13 of groove 11. More 10 specific reference to this will be had later.

The upper latch element 15 has its intermediate portion arcuate in plan and is provided at its forward end with an enlarged laterally extending nose 19 and is further provided with a cut away 15 portion or notch 20 to prevent the upper latch 15 from touching the rod when held within the slot 21. The rear end of each dog 15 is provided with a somewhat laterally off-set handle 22.

Figs. 3 and 4 show that the groove 11 receives a coil spring 23 which bears against a depending shoulder 24 carried by each dog 15. A pivot pin or stud 25' is also carried by the dog 15 and engages the opening 19' in the lower dog 15'. When in coupled position the lower dog fits on 25 the pin 25 slightly in advance of the shoulder 24. It is believed to be obvious that said spring 23 bearing against the shoulder 24 of each dog 15 serves to separate the handles 22 and thus urge 30 the nose portions of the dogs into relatively close proximity as shown in Fig. 1. Adjacent the shoulder 24 the handle portion of each dog 15 has a cut-out portion 25 so as to accommodate a flange 5', which constitutes the outer wall of the slot 11 as shown in Figs. 3 and 4. Thus the 35 bottom surface of the handle portion 22 will make a flat contact with the rearwardly extending shelf 5'' of the body. Each notch or cut-out portion also provides the lateral shoulder 25^a heretofore referred to; and when the stop 18 (Fig. 3) has engaged seat 17 of dog 15' the action 40 of spring 23 causes the rear portions of upper dogs 15 to rock outwardly in groove 11 about pivot 25', so as to cause the lateral shoulder 25^a of dog 15 to engage the groove tooth or shoulder 45 13 to prevent rearward sliding of the dog assemblies in groove 11.

The novel wear plate 16 which has been referred to incidentally hereinabove, is best shown in Fig. 5. It is noted that the central portion 50 of this plate is considerably thickened so as to provide a maximum strength at the point of contact by the work adjacent the slot 21 which matches with the slot 12 of the body 5. The end of the wear plate 16 opposite the slot 21 is indicated 55 at 26. As shown the portion 26 is adapted to overlie the rear ends or handles 22 of the dogs 15, so as to protect the same against injury. In other words the handle portions are slidingly confined 60 between the shelf portion 5'' of the body and the rear extension 26 of the wear plate.

The wear plate 16 is provided with side ledges 27 and an intermediate cut-out portion 28. The cut-outs 28 are adapted to receive the ends 9' of the pivot pins 9 and the ledges 27 are adapted 65 to permit the easy insertion and withdrawal of the cotter pins 10 from the transverse opening in the end 9'. Manifestly, the pivot pins 9 bearing against the wear plate 16 and more specifically bearing against the portion 28 will 70 confine the wear plate in place and thus hold the dogs and spring 15 in assembled relationship with the body 5.

When it is desired to remove the wear plate to replace a dog or any broken or worn part, it is only necessary to remove the cotter pins 10.

This having been done it is perfectly obvious that the pivot pins 9 can be moved outward so as to clear the sides of the wear plate 16, and the plate is thus freed for removal.

In operation a rod or tubing is inserted through 5 the opening 12. As the rod enters the opening it contacts with the upper dogs 15 causing the contraction of the spring 23 and the releasing of notches 25^a from association with lugs 13. With the continued urging of the rod into the opening 10 15 10 the lower dogs are struck and both pairs of dogs 15, 15' are actuated rearwardly against the action of spring 23 allowing the rod to enter the central opening 29 in the elevator. When thus positioned, the springs urge the dogs back to their 15 normal position whereupon the lugs 13 are engaged by the notches 25 and the rod is firmly locked in position. When the rod is to be released a pressing on the handles 22 will obviously 20 open the latch permitting the rod to be withdrawn.

When the handles are pressed together the first movement rocks the upper dogs out from engagement with the lugs 13 allowing the lower dogs to freely open to release the tubing or rod. 25 The purpose of the interengaging notches and shoulders 25^a, 13, and the dog construction described is to securely lock the rod in the inside opening of the elevator so that it cannot be disengaged by any friction of the rod from the inside of the dogs, but to also enable the rod to be readily inserted by pressure against the dog noses 19 from without work opening 12, 29. This causes an initial rocking of the rear ends of dogs 30 35 15 inwardly in groove 11 to disengage shoulders 25^a from the groove shoulders, or teeth 13,—so that the dog assemblies are free to slide rearwardly in grooves 11 against the action of spring 23. Shoulders 25^a, 13 will have disengaged before the work that is being inserted comes into engagement with dogs 15'. The latter are at all times 40 free to slide rearwardly when shoulders 25^a, 13 are disengaged; and their outer ends may be rocked inwardly, but not outwardly.

It is to be noted that the stop elements 18 are 45 shown as set screws but obviously the elements could be formed integral with the body portion 5 to serve the same function. These elements serve to stop or limit the outward movement of the dogs and to hold the same in proper place 50 so that the upper dogs are properly and normally seated and held by the lugs 13. When the lower dogs engage the stop elements the upper dogs are permitted to drop behind the lugs 13 and tend to hold the lower dogs securely closed; and opening 55 of the same from any friction of the rod is prevented when latched around the same.

The advantage of having the cut-out portion 20 on the upper latches or dogs is to prevent the upper dogs from touching the rod when latched 60 around the same, thereby preventing the accidental tripping and uncoupling of the rod from the dogs from the inside of the rod elevator.

It is to be understood that the form of my invention herewith shown and described is to be 65 taken as a preferred embodiment of the same, and that various changes in the shape, size, and arrangement of parts may be resorted to without departing from the spirit of my invention or the scope of the subjoined claims.

For instance, no invention would be involved 70 over the disclosures herein by using a single closure 15, 15' instead of a double closure. Also, it is to be noted that member 15 serves as a combined latch and operating member for the com- 75

panion member 15'; and that nose 19 of member 15 guides the work into opening 12, 29 in addition to releasing portions 13, 25^a from engagement. And, furthermore, the key or member 10 (Fig. 5) engaging ledge 27 holds the eccentric end of pin 9 from turning out of pressure contact with ledge 27.

Having thus described my invention what I claim is:

10. 1. The combination with an elevator; of a detachable wear plate having side ledges thereon, removable bail attaching eccentric pins, said pins adapted to overlie said wear plate to hold the same in place, and pins arranged on said ledges and adapted to engage the ends of said eccentric pins for fastening the same in position.

2. In a device of the class described, a body having a work-receiving opening, duplicate latch members comprising upper and lower pivotally connected latch elements arranged in said body and normally closing said opening, stop means carried by the body portion and adapted to engage the lower latch members to limit the outward movement thereof, a detachable wear plate for holding said latch members and body assembled, means for engaging said wear plate to hold the same in place, and said upper latch element having means to prevent its contact with the work in said opening whereby to prevent accidental release of the latch members.

3. In a device of the class described, a body having a work receiving opening, duplicate latch members comprising upper and lower latch elements arranged in said body, said elements being pivotally connected to each other and adapted to close the work receiving opening, a detachable wear plate having a work receiving opening therein arranged over said latch elements and confining the same between the body portion and the wear plate, teeth carried by said body, and said upper latch elements having portions normally engaged and held by said teeth.

4. In a device of the character described, a body portion having a work receiving opening therein, duplicate upper and lower latch elements pivotally arranged within said portion and adapted to close said opening, and a removable wear plate having a work receiving opening arranged and secured over said latch elements, and means whereby said upper latch members are moved prior to the lower latch members.

5. A pipe elevator or the like comprising a body having a side slot providing a work-receiving opening, a closure for said slot comprising pivotally connected superposed dog elements, said body providing a guide slidably receiving said dog element-provided closure, one of said dog elements being movable transversely in said guide and having means cooperable with a part of said body for holding said closure closed, and the other dog elements being sustained against transverse movement in said guide and having a portion disposed in said slot in advance of said first-named dog element whereby to prevent accidental engagement and release of the same.

6. A pipe elevator or the like comprising a body having a side slot providing a work-receiving opening, a closure for said slot comprising a pair of superposed and connected dog elements, means movably connecting said dog element-provided closure to said body for movement to and from operative position, one of said dog elements being movable relatively of the other, a locking stop on said body and engageable by said relatively movable dog element to lock the closure in closed

position, and said other dog element having a portion projecting laterally beyond said relatively movable dog element at the site of said slot whereby to prevent accidental striking of the latter to release the closure.

7. A pipe elevator or the like comprising a body having a work opening, a pair of bail-supporting ears formed at opposite ends of said body, a wear plate positionable upon said body about said work opening, said wear plate being cut away at its sides adjacent said ears to provide laterally extending bottom ledges and inwardly extending recesses communicating with said ledges, said ears having transverse pin-receiving holes, the lower portions of said holes being below the plane of said ledges, securing pins insertible in said ears and having eccentric inner terminals engageable in said recesses and bearable upon said ledges to clamp the wear plate upon said body, and securing keys for said pin terminals and supportable upon said ledges.

8. A pipe elevator or the like comprising a body having a work opening, a pair of bail-supporting ears formed at opposite sides of said body, a wear plate positionable upon said body about said work opening, said wear plate being cut away at its sides adjacent said ears to provide laterally extending bottom ledges, said ears having transverse pin-receiving holes, the lower portions of said holes being below the plane of said ledges, securing pins insertible in said ears and having eccentric inner terminals bearable upon said ledges to clamp the wear plate upon said body, and securing keys for said pin terminals and supportable upon said ledges.

9. A pipe elevator or the like comprising a body having a work opening, a pair of bail-supporting ears formed at opposite sides of said body, a wear plate positionable upon said body about said work opening, said wear plate being cut away at its sides adjacent said ears to provide laterally extending bottom ledges, cooperating with the adjacent ears to provide key-receiving grooves, pins extending transversely through said ears and bearing upon said ledges, and keys extending through said pins and resting upon said ledges in said grooves to hold said pins in clamping engagement with said wear plate.

10. A pipe elevator comprising a body having a side slot providing a work receiving opening, a body-carried closure for said opening, a latch carried by said closure and movable relatively of the same, said latch and body having interengageable portions for holding said closure closed, and said latch having a combined latch releasing and work guide portion at the exterior side of said closure and operable to release the closure and guide the work into said work opening upon engagement of the work thereagainst.

11. A pipe elevator comprising a body having a side slot providing a work receiving opening, a body-carried closure for said opening, a latch carried by said closure and movable relatively of the same, said latch and body having interengageable portions for holding said closure closed, said latch having a combined latch releasing and work guide portion at the exterior side of said closure and operable to release the closure and guide the work into said work opening upon engagement of the work thereagainst, said closure having a portion interposed between said latch and the work within said opening whereby to prevent accidental release of the latch.

12. A pipe elevator comprising a body having a side slot providing a work receiving opening, a body-carried closure for said opening, a latch carried by said closure and movable relatively of the same, said latch and body having interengageable portions for holding said closure closed, said latch having a combined latch releasing and work guide portion at the exterior side of said closure and operable to release the closure and guide the work into said work opening upon engagement of the work thereagainst, and a combined latch and closure operating lever carrier by said latch member.
13. A pipe elevator comprising a body having a side slot providing a work receiving opening, a body-carried closure for said opening, a latch carried by said closure and movable relatively of the same, said latch and body having interengageable portions for holding said closure closed, said latch having a combined latch releasing and work guide portion at the exterior side of said closure and operable to release the closure and guide the work into said work opening upon engagement of the work thereagainst, said closure having a portion interposed between said latch and the work within said opening whereby to prevent accidental release of the latch, and a combined latch and closure operating lever carried by said latch member.
14. In a pipe elevator comprising a body having a side slot providing a work opening and a closure therefor, the combination of a work and hand operable combined latch and closure operator member shiftably carried by said closure, a work guide on said member at the exterior side of said closure adjacent the entrance to said opening, and an operating handle carried by said member at a point remote from said work opening entrance.
15. In a pipe elevator comprising a body having a side slot providing a work opening and a closure therefor, the combination of a work operable combined latch and closure operator member shiftably carried by said closure, and a work guide on said member at the exterior side of said closure adjacent the entrance to said opening.
16. In a pipe elevator comprising a body having a side slot providing a work opening and a closure therefor, the combination of a work operable combined latch and closure operator member shiftably carried by said closure, a work guide on said member at the exterior side of said closure adjacent the entrance to said opening, and a portion of said closure interposed between said member and the interior of said work opening to prevent accidental tripping of said latch.
17. In a pipe elevator comprising a body having a side slot providing a work opening and a closure therefor, the combination of a work operable combined latch and closure operator member shiftably carried by said closure, a work guide on said member at the exterior side of said closure adjacent the entrance to said opening, said body having a top surface groove slidably receiving said closure and latch member, a wear plate upon said body cut away at opposite sides to provide laterally projecting ledges, bail-receiving ears opposite said ledges and cooperating with the ledges and superjacent sides of the body to provide grooves, bail retaining pins insertable transversely through said ears and having their inner ends resting upon said ledges, and keys insertable in said grooves along said ledges and through said pins to lock said wear plate upon said body for holding said closure and latch in place.
18. In a pipe elevator comprising a body having a side slot providing a work opening and a closure therefor, the combination of a work operable combined latch and closure operator member shiftably carried by said closure, a work guide on said member at the exterior side of said closure adjacent the entrance to said opening, said body having a top surface groove slidably receiving said closure and latch member, a wear plate upon said body cut away at opposite sides to provide laterally projecting ledges, and body-carried pins engaging said ledges for holding the wear plate in place.
19. In a pipe elevator comprising a body having a side slot providing a work opening and a closure therefor, the combination of a work operable combined latch and closure operator member shiftably carried by said closure, a work guide on said member at the exterior side of said closure adjacent the entrance to said opening, said body having a top surface groove slidably receiving said closure and latch member, a wear plate upon said body cut away at opposite sides to provide laterally projecting ledges, body carried bail holding pins having eccentric ends engaging said ledges, and keys on said ledges extending through said pins to hold them in clamping engagement with said ledges.
20. In a pipe elevator or the like comprising a body, a detachable wear plate positionable upon said body, and means for clamping said plate upon said body and including a laterally extending substantially horizontal side ledge on said plate, and a body-carried bail holding pin having an eccentric inner end engageable with said ledge substantially throughout the width of same.
21. In a pipe elevator or the like comprising a body, a detachable wear plate positionable upon said body, and means for clamping said plate upon said body and including a laterally extending side ledge on said plate, a body-carried bail holding pin having an eccentric inner end engageable with said ledge, and a key on said ledge extending into said eccentric pin end to hold it in clamping engagement with said ledge.
22. A pipe elevator or the like comprising a body having a frontal slot providing a work-receiving opening, a circular groove in the top face of said body and laterally enlarged at opposite sides of said slot, duplicate dog assemblies in said groove at opposite sides of said slot, laterally projecting nose portions carried by each of said dog elements at the ends adjacent said slot, the nose portions of the subjacent dog elements working on said groove enlargements and sustained by the outer walls of such enlargements against transverse movement in said groove, the upper dog elements being rockable slightly transversely of said slot and subjacent dog element and having the front and rear ends of their nose portions which overlie the slot disposed forwardly of corresponding portions of the nose of the subjacent dog members, means tending to actuate said dog member assemblies to slot-closing position, stops in said slots and engaging the noses of the lower dog members for limiting the closing movement of said dogs assemblies, teeth provided in the rear side portions of said slot, and the upper dog members having lateral shoulders normally engaging said teeth when the dog assemblies are in slot closing position for so maintaining the same.
- JOSEPH F. MOODY. 75
